UNITED STATES PATENT OFFICE.

SAMUEL HENRY BYRNE, OF BRIGHOUSE, COUNTY OF YORK, ENGLAND.

APPARATUS FOR DRAWING WIRE.

SPECIFICATION forming part of Letters Patent No. 331,680, dated December 1, 1885.

Application filed July 15, 1885. Serial No. 171,689. (No model.)

To all whom it may concern:

Be it known that I, SAMUEL HENRY BYRNE, a subject of the Queen of Great Britain, residing at Brighouse, in the county of York, 5 England, wire-manufacturer, have invented certain new and useful Improvements in Apparatus for Wire-Drawing, of which the following is a specification.

This invention has for its object improvements in apparatus for wire-drawing.

My invention is especially applicable when drawing wire at one operation through a series of rotating dies, as is described in the specification of a former patent granted to me June 15 9, 1885, No. 319,556; but it is also applicable when drawing wire in other ways.

The invention relates to the dies through which the wire is drawn.

The dies which I employ are of the mineral 20 known as "bolus" or "pea bort." The eye is drilled in the mineral in the same way as diamonds and other jewels have heretofore been drilled for wire-drawing, and the stone is in like manner set firmly in a metallic setting. 25 The usual way is to insert the stone into a hole in a piece of sheet-brass, and there retain it by the aid of tin or fusible metal.

In order that my said invention may be most fully understood and readily carried into 30 effect, I will proceed to describe the drawings hereunto annexed.

In the drawings, Figure 1 is a side elevation, and Fig. 2 is a plan, indicating the arrangements of the machine which I employ. Figs. 35 3 and 4 show separately, to a larger scale, one of the die-holders and parts immediately in connection therewith; and Figs. 5 and 6 show the die which is received into the said holder.

The frame *a* carries the bearings for the axis 40 of the pulleys *b*, *b*², *b*³, *b*⁴, and *b*⁵, and by suitable driving-gears these axes can be so driven as to give any desired surface-speed to the periphery of the pulleys. *c* is a drum, also carried by the frame and capable of turning 45 freely. Upon it is placed the wire as it is brought to the machine, and the wire unwinds from this drum as it is drawn forward through the dies. *d* is another drum on which the wire is wound as it comes from the dies. The axis 50 of this drum is driven in order that the drum

may wind up the wire as it is delivered to it. *e*', *e*², *e*³, *e*⁴, and *e*⁵ are brackets on the frame carrying the dies.

The dies consist of bolus or pea bort perforated and set concentrically in a metal disk, 55 and this is inserted into a holder which is provided with a hollow axis through which the wire passes. The holder in each case has spur-teeth upon its periphery, which engage with corresponding teeth upon a pinion on an axis, *f*, which is slowly rotated in order to impart a continuous rotary motion to the dies while the machine is in action. In all these features, excepting the use of bolus or pea bort in the die, the machine resembles that 65 for which a patent has already been granted to me, No. 319,556.

The wire passes into the machine from the drum *c*, first through the die on the bracket *e*', thence once around the pulley *b*', next through 70 the die at *e*², and to the pulley at *b*², and so on until it arrives at the receiving-drum *d*. The surface-speeds of the pulleys *b*', *b*², *b*³, *b*⁴, and *b*⁵ are carefully adjusted to accord with the extensions of the wire resulting from its passage through the dies. 75

f', *f*², *f*³, *f*⁴, and *f*⁵ are nozzle-tubes on the pipe *f*, and stop-cocks are provided in connection with them. The nozzles, of which the openings may be an eighth of an inch in diameter, are so directed that the streams of liquid issuing from them impinge in each case at the eye of the die. The liquid which I have found most suitable for the lubrication of the dies or for application to the dies in this manner is prepared by boiling one part of soft-soap with thirty parts of water until perfect solution is obtained. 80

Beneath the pulleys *b*', *b*², *b*³, *b*⁴, and *b*⁵ a trough or troughs are provided, in which the 90 said pulleys are immersed nearly up to their axes. This trough, to avoid confusion, is not represented in the drawings. It catches the liquid issuing from the jets after it has impinged upon the dies. This liquid is returned 95 to the cistern in any convenient manner.

Bolus or pea bort is a form of carbon found in the beds which also yield diamonds. The shape it takes is that of pea-like balls, either clear or more or less colored. It will not 100

cleave like the diamond in parallel planes, but its structure is radial. It is both tougher and harder than diamond.

In the use of diamonds in the machine above described, the loss by breakage is found to be very serious, not only on account of the cost of the gem, but also and mainly on account of the delay in working, to which such breakages give rise.

10 When the eye is formed in bolus or pea bort, the stone rarely breaks, and such dies are very durable.

15 My invention is applicable not only to the drawing of wire of iron and steel, but also to drawing wire of copper or brass, and specially fine wire. Wire of any metal from which wire is usually made, and wire of various sizes, may be produced in accordance with my invention.

20 My invention also, although especially advantageous when drawing at one operation through several rotating dies, is nevertheless useful in wire-drawing by the more usual and simpler methods.

I claim as my improvements in wire-draw- 25 ing and in apparatus employed therein—

1. A die for drawing wire having the eye formed in the stone or mineral called bolus or pea bort.

2. As an improvement in an apparatus for 30 wire-drawing, a series of dies having eyes formed in bolus or pea bort, through which series of eyes the wire is drawn continuously at one operation.

3. As an improvement in apparatus for 35 wire-drawing, a series of dies which are caused continuously to rotate, and which have eyes formed in bolus or pea bort, through which the wire is drawn continuously at one operation.

SAMUEL HENRY BYRNE.
